UNITED STATES PATENT OFFICE.

CHARLES F. RUBY, OF ST. LOUIS, MISSOURI, ASSIGNOR TO MISSOURI LOCOVOLO COMPANY, OF ST. LOUIS, MISSOURI, A CORPORATION OF MISSOURI.

STEAM-GENERATOR.

SPECIFICATION forming part of Letters Patent No. 766,904, dated August 9, 1904.

Application filed July 13, 1903. Serial No. 165,281. (No model.)

To all whom it may concern:

Be it known that I, CHARLES F. RUBY, a subject of the Emperor of Austria-Hungary, residing at St. Louis, Missouri, have invented 5 a certain new and useful Improvement in Steam-Generators, of which the following is a full, clear, and exact description, such as will enable others skilled in the art to which it appertains to make and use the same, reference 10 being had to the accompanying drawings, forming part of this specification, in which—

Figure 1 is a sectional elevational view of my invention; and Fig. 2 is a plan view, partly in section.

15 This invention relates to new and useful improvements in steam-generators designed particularly for use in connection with automobiles, the object being to simplify the construction of devices of this character, where- 20 by steam may be generated quickly and economically.

25 Referring to the drawings, 39 indicates a casing, bolted or otherwise secured to the casting, which carries bars 29. This shell or casing 39 is preferably cylindrical.

30 40 indicates a flanged ring, secured to the shell 39 and provided with openings 41, which are the escape-openings for the products of combustion from the generator. This flanged 35 ring carries a shell or casing 42, which is attached to the top plate 43, said top plate also having the shell 39 connected to it. A removable cap or cover 44 is carried by the top plate, by removing which access may be gained 40 to the combustion-chamber of the generator. Openings 45 are provided in the shell 39 near its outer edge, through which the products of combustion pass on their way from the combustion-chamber to the escape-openings 41.

45 For the sake of distinction I will term the chamber or annular space formed by the shell 39 and the flanged ring 40, the shell 42, and the top plate 43 as the "primary" heating-chamber. In this primary heating-chamber is located a coil or coils of pipe 46, into the lower extremities of which water is supplied by means of a suitable header through the pipe 9. A core 46^a is arranged in this feed-water pipe, said core being in the form of a

wire, for restricting the water-passage and 50 also for distributing the heat throughout the water uniformly. Openings 41 are covered by wire-gauze, and the primary heating-chamber around the coils 46 is preferably packed with metallic turnings or shavings, which 55 interrupt the products of combustion and retain and impart heat to coils 46, so that water passing therethrough will be initially heated. Upon reaching the upper terminals of coils 46 the water so initially heated is received 60 into a header or manifold and by a suitable pipe connection led into the top flasher-section 47. This flasher-section is preferably a casing observing substantially a U shape, 65 suitable openings leading from the passage 70 thevein for the purpose of removing the core. These openings are subsequently plugged for obvious reasons. The water from the primary heater is in communication with one leg of the U-shaped passage and after trav- 75 ersing the said passage is led down at the extremity of the other leg of the passage by a pipe 48 into the next adjacent flasher-section. The water or steam is caused to traverse this 80 flasher-section and pass thence through a pipe to the next flasher-section, which is traversed and the steam led therefrom through the pipe 12. All of these flasher-sections are prefer- 85 ably made from the same pattern, and each section is provided with heat retaining and conducting flanges 49, which are so disposed as to engage the shell 39 for the purpose of holding the flasher-sections immovably in position. Other means may be employed for holding these sections in place; but by making 90 like flasher-sections it will be obvious that considerable saving is effected in the cost of manufacture thereof. Into one of these flasher-sections is screwed a plug 50, which serves the double function of closing one of the core- 95 openings and of supporting the vaporizing-plug 23 of the temperature regulating and controlling device. Into the passage of the lowermost flasher-section is introduced a coil-spring 51, the purpose of which is to restrict the water-passage in said flasher-section. This coil-spring can be conveniently introduced through the core-opening, and by reason of

the small area of contact with its inclosing flasher-section this spring is naturally of lower temperature than the flasher-section, and consequently assists in converting the water into steam. These flasher-sections are preferably formed from cast-steel, and, as is well known, to form the passage therein a core must be employed in forming the casting. This core is necessarily larger than the size of the opening required in the finished flasher-sections for the water-passage, and to reduce the size of said passage the coil-springs are introduced therein, as shown. While I have described the coil-spring as being arranged in the lowermost flasher-section, it is obvious that springs can be employed in the other flasher-sections, also that other means may be employed for the purpose of reducing the water-passage in said flasher-sections.

20 In the combustion-chamber of the generator and around the lowermost flasher-section is packed granulated refractory material, preferably of magnesite or other well-known fire-resisting substance. This granulated refractory material is supported by the bars 29, and adjacent said bars the particles are finely divided, they increasing in size until the middle flasher-section is reached. Above the middle flasher-section the combustion-chamber is open. In this manner connected air-spaces are formed from the burner to the open space in the top of the combustion-chamber, said connected air-spaces, by reason of the increment in size of the particles of refractory material, gradually increasing toward the open space. In starting the burner it has been noticed that the mixed air and gas will be consumed well up in the refractory material, at the beginning burning with some considerable flame in the open chamber at the top of the combustion-chamber. As the refractory material becomes heated the flame decreases, and finally in the normal operation of the device the mixture will combust by catalytic action and be located close to the burner-bars 29, the refractory material becoming incandescent, so that perfect combustion follows and a most efficient burner results. It has been found that the surface area of refractory material exposed to the combustible mixture greatly influences the capacity of the generator for burning said mixture, as well as the capability of the device for burning the gases by catalytic action. On the other hand, catalytic combustion will only take place when the refractory material is heated to a rather high temperature. Thus in order to expose a large surface of the refractory material to the gases I introduce small granulated particles of refractory material in the bottom of the combustion-chamber and increase the size of said particles toward the top of the space occupied by the refractory material. In starting the burner the large cool surface exposed by the smaller granulated par-

ticles, with their small interstices or connected air-spaces, will prevent combustion close to the burner, and likewise this fact will also retard the heating up of these small particles to the temperature where catalytic combustion will take place. As the larger pieces of granulated refractory material present larger spaces to be occupied by the gases, combustion will take place in these larger spaces and heat the larger pieces of granulated material to a considerable extent. This heat will by radiation raise the temperature of the smaller granulated particles up to a point where catalytic combustion will take place in a zone adjacent to the bars 29. Combustion of the gases occurring in such a heated mass as these finer particles of granulated material will take place in an extremely short length of time, and thus restrict the zone of combustion within the finer particles of granulated material and at the same time prevent the intermixing of the products of combustion with the incoming fresh gas. This fact also contributes to complete combustion in a restricted zone, where the gases are introduced under any desired pressure, so that the products of combustion can be directed to any desired point without additional help, such as a forced draft, &c.

Having thus described my invention, what I claim as new, and desire to secure by Letters Patent of the United States, is—

1. In a steam-generator, the combination with generator-sections having heat collecting and retaining flanges, of a combustion-chamber in which said sections are located, particles of refractory material surrounding one of said sections and in close contact with its flanges, there being interstices between said particles, and a fuel-supply nozzle arranged exteriorly said combustion-chamber; substantially as described.

2. In a steam-generator, the combination with a combustion-chamber, of generator-sections arranged therein and provided with heat collecting and retaining flanges, particles of refractory material in which the flanges of the lowermost section are buried, and a fuel-supply nozzle arranged exteriorly said combustion-chamber; substantially as described.

3. In a steam-generator, the combination with a combustion-chamber, of generator-sections arranged therein, and stratified particles of refractory material in said combustion-chamber, the upper stratum of said refractory material being the coarser; substantially as described.

4. In a steam-generator, the combination with a combustion-chamber, of a burner located at one side thereof, generator-sections in said combustion-chamber, and stratified refractory material arranged in said combustion-chamber approximate to the burner, the strata nearest the burner being the finer; substantially as described.

5. In a steam-generator, the combination

with a combustion-chamber, of a burner arranged at one side thereof, generator-sections in said combustion-chamber, granulated refractory material in said combustion-chamber and approximate to said burner, at least one of said sections being buried in said refractory material, the other of said sections having free space therearound, and an opening for the products of combustion leading from 5 said space; substantially as described.

6. In a steam-generator, the combination with a combustion-chamber, of generator-sections arranged therein and having circumferential flanges, the flanges of one of the sections 10 alining with those of the other, and

particles of refractory material in said combustion-chamber and entirely surrounding one of the sections; substantially as described.

7. A steam-generator having generator-sections provided with alining flanges, the lower 20 section and its flanges being surrounded by and in close contact with a granular material; substantially as described.

In testimony whereof I hereunto affix my signature, in the presence of two witnesses, 25 this 16th day of June, 1903.

CHARLES F. RUBY.
